CLAIM

The ornamental design for a lens support ring for a digital camera, as shown.

DESCRIPTION

FIG. 1 is a perspective view of the front, top and left side of a lens support ring for a digital camera showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear view; and,

FIG. 7 is a bottom plan view thereof.

The broken line showing of a camera is to illustrate environment only and forms no part of the claimed design.
